Primary Examiner — Natasha Vujcic*Assistant Examiner* — Gilbert B Ford(74) *Attorney, Agent, or Firm* — Blank Rome LLP**CLAIM**

The ornamental design for a liquid transfer device, as shown and described.

DESCRIPTION

FIG. 1 is a rear perspective view of a liquid transfer device according to a first embodiment;
FIG. 2 is a front view thereof;
FIG. 3 is a rear view thereof;
FIG. 4 is a left side view thereof;
FIG. 5 is a right side view thereof;
FIG. 6 is a top view thereof; and
FIG. 7 is a bottom view thereof.
FIG. 8 is a front perspective view of a liquid transfer device according to a second embodiment;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.

The broken lines in the figures show portions of the liquid transfer device that form no part of the claimed design.

1 Claim, 14 Drawing Sheets(56)
